UNITED STATES PATENT OFFICE.

FREDERICK JARRY, OF NEW BEDFORD, MASSACHUSETTS.

TENSION DEVICE FOR SPOOLING-MACHINES.

1,329,341.

Specification of Letters Patent. Patented Jan. 27, 1920.

Application filed August 14, 1919. Serial No. 317,511.

To all whom it may concern:

Be it known that I, FREDERICK JARRY, a citizen of the United States, residing at New Bedford, in the county of Bristol and State 5 of Massachusetts, have invented certain new and useful Improvements in Tension Devices for Spooling-Machines, of which the following is a specification.

This invention relates to certain new and 10 useful improvements in tension devices for spooling machines, and the primary object of the invention is to provide a rolling or rotatable tensioning means and to also provide means for adjusting the tension of the 15 rolling means as desired. The invention further aims to provide a simple and effective structure involving a minimum of parts easily accessible and unlikely to be easily deranged.

20 Briefly, the invention proposes a rotatable or turnable roller over or around which the thread passes and a device under the influence of an adjustable counter-weight or the equivalent for placing the axle or supporting shaft of the roller under adjustable tension.

In the drawings, illustrating an embodiment of the invention,

Figure 1, is a top plan view;
30 Fig. 2, is a side elevation; and
Fig. 3, is a section taken on line 3—3 of Fig. 2.

In proceeding in accordance with the present invention a roller 1, is rigidly mounted 35 on or in rigid connection with a supporting shaft or axle 2 the latter mounted in a journal 3, the journal being here shown, by way of example as carried by a standard 4 extending upwardly from a base 5. The journal is 40 provided with a cut-out 6 which at one end communicates with the axle 2 and is radial to the latter. A brake block or friction shoe 7 is slidably mounted in the cut-out 6 and is guided by the walls defining the latter. The 45 block at its inner end is grooved at 8 to conformably receive the axle and is similarly grooved at 9 at its outer end to receive a lever rod 10 which latter is pivoted at 11 to a vertical arm 12. Arm 12 is offset from its 50 lower part 12' the latter being projected through the journal. The grooves 8 and 9 are disposed at a right angle to each other and likewise the axle and lever rod 10. A counterweight 13 is adjustable along the

lever 10, so as to vary the tension on the 55 shoe 7 and accordingly the tension or braking action of the shoe on the axle.

An eye 14 is carried by the base and located on one side of the roller 1, while a hook 15, on the base is located on the opposite side of the roller.

In operation, the yarn from the spool situated below the eye 14, passes through the latter and once around the roller 1 and thence under the hook 15, to the spool adjacent the hook, the tension being created by the braking action or force of the shoe 7, which retards rotation of the roller axle according to the position of the weight.

As is obvious from the foregoing, a simple 70 and economical structure is provided in which the shoe may be removed and replaced by simply lifting same subsequent to disengagement of the lever rod therefrom.

What is claimed is:

1. In a tension device for spooling machines, a journal having a cut-out therein, an axle in the journal communicating with the cut-out, a braking shoe slidably in the cut-out and having a groove on its inner end receiving the axle and a groove on its outer end at right angles to the first named groove, an arm on the journal, a counterweighted lever pivoted to the arm and engaged in said groove of the outer end of the shoe, a thread 85 engaging roller on the axle, and thread guiding members on opposite sides of the roller and located therebelow.

2. In a tension device for spooling machines, an axle, a yarn engaging roller borne 90 by the axle, a friction shoe engaged at one end with the axle, means to slidably mount the shoe, a pivoted lever bearing between the ends thereof on the opposite end of the shoe, and a weight adjustable on the lever.

3. In a tension device for spooling machines, an axle, a yarn engaging roller borne by the axle, a friction shoe engaged at one end with the axle, means to slidably mount the shoe, a pivoted lever bearing between its 100 ends on the opposite end of the shoe, and means to adjustably tension the lever.

4. In a tension device for spooling machines, an axle, a yarn engaging roller on the axle, a friction shoe of bar-like form, means 105 to mount said shoe to allow same to slide radially of the axle and to bear at one end on the latter, and means engaged with the

other end of the shoe to adjustably tension the latter.

5. In a tension device for spooling machines, an axle, a yarn engaging roller on the 5 axle, a friction shoe of bar-like form, means to mount said shoe to allow same to slide radially of the axle and to bear at one end on the latter, and a lever pivoted at one end and counterweighted at its opposite end, said 10 lever overlying the shoe and bearing thereon at a point intermediate of its ends, whereby the shoe may be slid out of engagement with

the axle by swinging of the lever out of engagement with the shoe.

6. In a tension device for spooling machines, a journal having a cut-out therein, an axle in the journal communicating with the cut-out, a bar-like braking shoe slidable in the cut-out and having its inner end bearing on the axle, and means engaging the outer 15 20 end of the bar-like shoe to tension the same.

In testimony whereof I affix my signature.

FREDERICK JARRY.
